UNITED STATES PATENT OFFICE.

MARTHA McPHERSON, OF NEW YORK, N. Y.

SKIRT-SUPPORTER.

SPECIFICATION forming part of Letters Patent No. 769,108, dated August 30, 1904.

Application filed December 18, 1903. Serial No. 185,667. (No model.)

To all whom it may concern:

Be it known that I, MARTHA McPHERSON, a citizen of the United States of America, and a resident of the borough of Manhattan, New York city, State of New York, have invented certain new and useful Improvements in Skirt-Supporters, of which the following is a specification.

My invention relates more particularly to skirt-supporters, but is also applicable for supporting trousers. It consists of an improved form of buckle adapted for ready attachment to a shirt-waist, vest, or like garment near the lower edge for its support and having hooks on which to suspend the skirt, trousers, or other garment, as hereinafter described, reference being made to the accompanying drawings, in which—

Figure 1 is an elevation, with a part turned down, of a skirt suspended from a shirt-waist by my improved supporter. Fig. 2 is a perspective view of the supporter detached from the garments, with dotted lines illustrating the jointed connection of the members of the supporter.

A represents the back portion of a shirt-waist, and B a skirt to be supported on the waist, for which I provide a buckle comprising two sheet-metal or flat-bar jaws *a* and *b*, whereof jaw *a* has a lateral arm *c* at each extremity, both projecting in the same direction, and has a series of hooks *d* at intervals along the edge that is opposite to the one having said lateral arms, and jaw *b* has a lateral arm *e* at one end and at the other end is pivoted at *l* to one side of one of the lateral arms *c* of jaw *a*, so that arm *e* overlaps the other lateral arm *c* of jaw *a*, said arm having a stud *f* and arm *e* having a slot *g*, in which said stud engages to clasp the two jaws together when closed in parallel relation to each other, and arm *e* is sprung over the head of the stud. Any other approved means of fastening these ends of the jaws may of course be employed, and I do not limit myself to the particular means herein shown.

The jaw *b* has a series of spurs or teeth *h* along the edge fronting jaw *a* and being about equal in length to the width of the space *i* provided between the two jaws by the lateral arms connecting them.

In the use of the supporter it is first opened, as indicated in dotted lines in Fig. 2. Then jaw *b* is pinned onto a fold *j* of the lower margin of the shirt-waist by the teeth, and jaw *a* is closed up and fastened to jaw *b* by the stud *f*, and the band *k* of the top of the skirt is then hooked onto hooks *d*, so as to be effectually and substantially connected, and the supporter is concealed from view.

The supporter being detachably connected to the waist may be readily set higher or lower, as may be preferred, and one supporter may serve for any number of dresses, while such supporters as have to be sewed on may not be as readily adjusted nor changed from one dress to another.

It will be noted that the construction is very simple and cheap. The two jaws with their respective spurs and hooks may be stamped out of sheet metal and be punched at the same time for the pivot and the fastening-stud, the hooks being subsequently bent.

What I claim as my invention is—

The combination in a garment-supporter, of a jaw having lateral arms at its extremities at one edge, and a series of hooks at the other edge, and another jaw pivoted at one end to one of the said lateral arms, and provided with teeth at its edge fronting the other jaw, and means to fasten the free ends of the jaws together, the pivot and the said fastening means being arranged to space the jaws apart about the length of the teeth.

Signed at New York this 29th day of November, 1903.

MARTHA McPHERSON.
